UNITED STATES PATENT OFFICE.

BENJAMIN STEWART, OF DES MOINES, IOWA.

ARCH SUPPORT AND HEEL CUSHION.

Application filed January 29, 1924. Serial No. 689,812.

To all whom it may concern:

Be it known that I, BENJAMIN STEWART, a citizen of the United States, and a resident of Des Moines, in the county of Polk and 5 State of Iowa, have invented a certain new and useful Arch Support and Heel Cushion, of which the following is a specification.

The object of my invention is to provide a new and novel arch support and heel cushion 10 of simple, durable and inexpensive construction of the pneumatic type.

A further object is to provide such an arch support and heel cushion, so arranged and constructed that it can be mounted entirely 15 within a shoe, without any hard or rough parts in contact with the foot.

Another object is to provide such a device having under the heel portion a valve and valve casing in combination with a shoe having 20 a socket in the heel on the interior of the shoe to receive such valve and valve casing.

Still another object is to provide with such an arch support and heel cushion an insole having a tongue extending around 25 the rear portion of the device and provided with a hole to receive the valve casing.

With these and other objects in view, my invention consists in the construction, arrangement and combination of the various 30 parts of my arch support and heel cushion whereby the objects contemplated are attained, as hereinafter more fully set forth, pointed out in my claim, and illustrated in the accompanying drawings, in which:

Figure 1 is a perspective view of a shoe 35 with parts broken away to show my improved arch support and heel cushion therein, the insole being shown in section.

Figure 2 is a sectional view through a 40 shoe with my device installed therein.

Figure 3 is a top or plan view of an arch support and heel cushion embodying my invention; and

Figure 4 is a plan view of a portion of the 45 insole showing the tongue thereon.

It will be understood that my arch support and heel cushion may be varied in size and shape to fit different shoes and feet and be accommodated to the particular circumstances.

My arch support and heel cushion comprises an elongated resilient container or bag indicated in the accompanying drawings by the reference character 10 adapted to extend 50 from the back of the shoe under the heel forwardly under the arch of the foot to

the ball of the foot or a distance under the ball.

The air container or bag 10 may be of rubber or other suitable material and is preferably of substantially the same width from end to end. I prefer this form because with such form, there is not the likelihood of having so much air in the forward part of the container, as might tilt the foot upwardly 65 in front, when standing upright.

The heel portion of the bag 10 has on its under side a valve casing 11 to form a projecting stem, to anchor or hold the device in place as herein later referred to, in which 70 is an ordinary check valve 12, which may be of any desired kind for the purpose. The container has formed thereon a tube 11^a to receive the casing.

This casing 11 is designed to be projected 75 downwardly and be received in a socket 13 made of aluminum or any other suitable material in the heel of the shoe 14, as shown in Figure 2. The reception of the valve casing 11 in the socket 13 serves to hold the 80 arch support and heel cushion in proper position in the shoe for supporting the arch and cushioning the heel.

Secured to the forward edge of the arch support and heel cushion is an extension 15 85 of rubber or other suitable material shaped to fit the forward part of the interior of the shoe, as shown in Figure 3. The extension 15 serves to give a smooth surface for the foot and prevents rubbing or wear at the forward end of the bag or container 10.

The bag or container 10 is rounded at its rearward end to fit and cover the shoe heel and is preferably rounded at its forward end, as shown, and the extension 15 connects with the bag for a distance rearwardly of its forward end, as illustrated. The extension 15 being shaped to fit the shoe also serves to prevent lateral movement of the forward end of the bag or container 10. 100 This is of some importance in view of the fact that the bag is practically of the same width at both ends.

It will be seen that I have thus provided an arch support and heel cushion which 105 serves to absorb the shocks of walking and support the arch and cushion the heel. It is arranged entirely on the inside of the shoe. It is preferably of substantially the same width from end to end, so that too much 110 air will not be pressed forwardly when the user stands upright and thereby raise the

front of the foot too much, and yet the provision of the extension 15 gives a smooth surface and also helps to hold the arch support and heel cushion in place.

I preferably use with my improved arch support and heel cushion a sock lining 16 shaped to fit the inside of the shoe and to substantially cover the entire arch support and heel cushion and extension 15. The 10 sock lining 16 is somewhat flexible and yet should have some stiffness and may be made of any material suitable for the purpose.

At its rear end, the sock lining 16 has a flexible tongue 17 which is folded around 15 and under the rear end of the bag 10 and is provided with a hole 18 to receive the casing 11. This tongue 17 thus serves to hold the sock lining in position particularly against sliding forwardly in the shoe.

20 In preparation and use of my invention, the container is inflated with air according to the user's desire; then the sock lining is laid over it and the tongue 17 is folded around and under the rear end with the 25 casing 11 extended through the hole in the tongue. The entire device is then placed in

the shoe, with the casing 11 inserted downwardly into the socket 13.

Some modifications may be made in my invention without departing from the real spirit and purpose thereof, and it is my intention to cover by my claim any such modifications or changes in structure as may be reasonably included within its scope.

I claim as my invention:

In a structure of the class described, the combination of an arch support and heel cushion, comprising a pneumatic resilient air container having on its under side near its rear portion a small, downwardly projecting tubular extension, and a valve structure received in said extension, with a shoe having a recess in its heel opening into the shoe for receiving said extension and valve structure, a loose flexible sock lining for covering the pneumatic member having at its rear portion a tongue folded around and under the rear portion of the pneumatic member and provided with a hole receiving said tubular extension.

Des Moines, Iowa, January 22, 1924.
BENJAMIN STEWART.
